LINE CHOKE COIL

Myron J. Brown, Pittsburgh, Pa., assignor to
Westinghouse Electric Corporation, East Pitts-
burgh, Pa., a corporation of Pennsylvania

Application June 2, 1947, Serial No. 751,776

3 Claims. (Cl. 175—356)

1

The present invention relates to line choke coils, which are intended to be connected in series in a transmission or distribution line to carry the normal, relatively low-frequency power current, and to interpose a high impedance to high-frequency carrier currents, which may be superimposed on the power current for communication or other purposes. The choke coil of the present invention is particularly adapted for use in connection with carrier current telephone systems on rural lines, although its usefulness is not necessarily restricted to this particular application.

The principal object of the present invention is to provide a line choke coil of rugged, weather-proof and inexpensive construction.

Another object of the invention is to provide a line choke coil having a coil support which also serves as a strain insulator for the line, thus permitting the choke coil to be inserted directly in the line, instead of being separately mounted as has been necessary heretofore.

A further object of the invention is to provide a choke-coil construction in which a protective spark-gap device and coil terminals are mounted directly on the coil support itself, resulting in a simple and low-cost construction.

Other objects and advantages of the invention will be apparent from the following detailed description of a preferred embodiment, taken in connection with the accompanying drawings, in which:

Figure 1 is a view in elevation of a choke coil embodying the invention connected in a line;

Fig. 2 is an end view of one end of the choke coil;

Fig. 3 is a longitudinal section view, approximately on the line III—III of Fig. 2;

Fig. 4 is an end view of the other end of the choke coil; and

Fig. 5 is a top plan view of the coil support, with the coil broken away.

The choke coil of the present invention is intended to be connected in series in a transmission or distribution line, as shown in Fig. 1, where the coil 1 is shown connected in series between line conductors 2 and 3. The coil is designed to have low, or substantially negligible, impedance at the frequency of the power current, which is usually sixty cycles per second, and to have very high impedance at the frequency of the carrier currents which may be superimposed on the power current, which may be of the order of 100 or 150 kilocycles per second, for example.

The construction of the new choke coil is shown in detail in Figs. 2 through 5. The choke coil 1

2

is supported on a tubular coil support 4, which may be made of porcelain or other suitable insulating material. The coil support 4 preferably has a plurality of circumferential ribs or projections 5 on its outer surface, each of which is interrupted at two circumferentially spaced points to form, in effect, longitudinal grooves 6 extending through the ribs 5. A strain member 7 is secured within the tubular coil support 4. The strain member 7 may also be made of porcelain, or other suitable insulating material which has sufficient mechanical strength. As shown in the drawings, the strain member 7 is generally cylindrical and has two slots 8 and 9 formed in it in mutually perpendicular planes, one slot extending to one end of the strain member, and the other slot extending to the other end, for reception of the line conductors 2 and 3. The strain member 7 may be secured in the tubular coil support 4 in any suitable manner, as by glazing it in place if both members are made of porcelain. Terminals 10 and 11 of any suitable type are mounted on opposite ends of the tubular coil support 4 by threading them into internally threaded holes in the ends of the coil support.

The coil 1 is supported on the outside of the tubular coil support 4. The coil 1 preferably consists of a plurality of sections 12, which may be spaced apart in order to control the distributed capacitance so as to obtain the desired impedance at the carrier frequency, and which are connected together in series, as indicated at 13. The coil sections 12 do not rest directly on the coil support 4, but are supported and held in place by a mass of rigid insulating material 14, which is molded around the coil sections and which engages the ribs 5 on the coil support to hold the coil sections 12 rigidly in place. The insulating material 14 may be an asphalt-base cement, or any other suitable insulating material which can be molded in place and which is sufficiently weather-proof and moisture-resistant.

Since the coil 1 is to be connected in series in a line, it might be damaged by voltage surges on the line resulting from lightning strokes, switching operations, or other causes, and the coil is protected against such damage by means of a spark-gap device, which is mounted directly on the coil support 4. One end of the coil support 4 has a recess 15 formed in it, as clearly shown in Fig. 5, and the spark-gap device consists of two electrodes 16 and 17 mounted on the end of the coil support 4 and positioned to form a spark gap between them over the recess 15.

The electrodes 16 and 17 may be arcuate mem-

bers of brass, or other suitable metal, and they are connected across the coil 1. The electrode 16 is secured in place by means of a screw 18 threaded into an internally threaded hole in the end of the porcelain tube 4, and a copper strap conductor 19 is also clamped under the screw 18 in contact with the electrode 16. The conductor 19 extends longitudinally through one of the grooves 6 on the surface of the coil support 4 to the opposite end, and is clamped under the terminal 10 at that end in electrical contact with the terminal. One terminal lead 20 of the coil 1 extends through the insulating material 14 and is soldered to the conductor 19. Thus, the terminal 10 is electrically connected to one end of the coil 1 and to one electrode 16 of the protective gap. The other electrode 17 of the gap is clamped in position on the end of the coil support 4 by the terminal 11, and a copper strap conductor 21 is also clamped under the terminal 11, so as to be in contact with both the terminal and the electrode 17. The conductor 21 extends for a short distance longitudinally of the coil support in the other groove 6, and the other terminal lead 22 of the coil is soldered to the conductor 21, so that this end of the coil is electrically connected to the terminal 11 and to the electrode 17.

In use, the choke coil 1 is interposed directly in a transmission or distribution line as shown in Fig. 1. The line conductors 2 and 3 are looped through the respective slots 8 and 9 of the strain member 7, and the ends of the conductors are carried to the terminals 10 and 11, respectively, so that the coil is connected in series in the line. The strain member 7 takes the stresses imposed by the line conductors, and no stress is imposed on the coil support 4 or on the terminals. The coil 1 is protected from damage due to surge voltages on the line by the gap between the electrodes 16 and 17, which breaks down and bypasses the coil upon the occurrence of a dangerous surge voltage. Since the arc between the electrodes occurs opposite the recess 15, it is spaced away from the porcelain tube 4, and thus there is no danger of cracking or otherwise damaging the porcelain, even though the electrodes are directly supported on the end of the tube.

It should now be apparent that a line choke coil has been provided which is of inexpensive construction, and which is rugged and weather-proof. The new choke coil can be mounted directly in the line itself, thus avoiding the disadvantages of separate mounting and resulting in a simple, low-cost installation. The new choke coil is particularly suitable for use in carrier current telephone systems on rural distribution lines, where low cost is an important consideration, but it will be apparent that it may also be used in other types of carrier current systems.

A preferred embodiment of the invention has been shown and described for the purpose of illustration, but it is to be understood that various other embodiments are possible within the scope of the invention. The invention is not limited, therefore, to the particular details of construction shown, but in its broadest aspects, it includes all equivalent embodiments and modifications which come within the scope of the appended claims.

I claim as my invention:

1. A choke coil comprising a tubular member of insulating material, a slotted, insulating strain member secured within the tubular member, a rigid mass of insulating material supported on the tubular member, a coil comprising a plurality of series-connected multi-turn sections, said coil sections being embedded in said mass of insulating material and spaced apart axially of the tubular member, and terminal means for the coil on the tubular member.
2. A choke coil comprising a tubular member of insulating material, a slotted, insulating strain member secured within the tubular member, said tubular member having circumferential ribs on its outer surface and having a recess in one end thereof, a rigid mass of insulating material supported on the tubular member and engaging said ribs, a coil comprising a plurality of series-connected multi-turn sections, said coil sections being embedded in said mass of insulating material and spaced apart axially of the tubular member, terminal means for the coil on the tubular member, and two electrode members mounted on said one end of the tubular member and disposed to form a gap between them over said recess in the tubular member, said electrode members being electrically connected to said terminal means so that the gap is across the coil.

3. A choke coil comprising a tubular member of insulating material, a slotted, insulating strain member secured within the tubular member, said tubular member having circumferential ribs on its outer surface and having a recess in one end thereof, a rigid mass of insulating material supported on the tubular member and engaging said ribs, a coil comprising a plurality of series-connected multi-turn sections, said coil sections being embedded in said mass of insulating material and spaced apart axially of the tubular member, terminal means for the coil on opposite ends of the tubular member, two electrode members mounted on said one end of the tubular member and disposed to form a gap between them over said recess in the tubular member, means for electrically connecting one of said electrode members to the terminal means at one end of the tubular member, and means for electrically connecting the other of the electrode members to the terminal means at the other end of the tubular member.
